INVENTOR

United States Patent Office.

DESIGN FOR A COACH LAMP.

JAMES H. DOWNS, OF NEW HAVEN, CONNECTICUT, ASSIGNOR TO C. COWLES & CO., OF SAME PLACE.

Design No. 2,508, dated November 27, 1866.

SPECIFICATION.

TO ALL WHOM IT MAY CONCERN:

Be it known that I, JAMES H. DOWNS, of New Haven, in the county of New Haven, and State of Connecticut, have invented a new Design for Coach Lamp; and I do hereby declare the following, when taken in connection with the accompanying drawings and the letters of reference marked thereon, to be a full, clear, and exact description of the same, and which said drawings constitute part of this specification, and represent, in—

Figure 1, a front view, and in

Figure 2, a side view, and in

Figure 3, the body of the lamp, which constitutes the subject of this design.

This invention relates more particularly to the lights in coach lamps than to the general form of the other parts, and consists in circular projecting lights.

To enable others skilled in the art to manufacture my new design, I will proceed to describe the same as illustrated in the accompanying drawings.

A is the socket, B the body, and C the top, of any desired form or configuration. The lights which constitute the subject of this invention are represented in fig. 3 as detached from the socket and top of the lamp, which said socket and top form no part of this design and are the front light D, the side light E, and the inside light F; that is to say, three-way lights. The front light D, as seen in fig. 2, is of circular form, and set in a frame projecting from the body B. The light E is of like form and in like manner projecting from the body.

What I claim, is—

The herein-described design for the lights of coach lamps, substantially as specified.

Witnesses:

JOHN E. EARLE,

A. J. TIBBITS.
